UNITED STATES PATENT OFFICE

147,225

DESIGN FOR A COMBINED WALLET AND KEY HOLDER

Murray Block, New York, N. Y.

Application April 3, 1947, Serial No. 138,134

Term of patent 7 years

(Cl. D87—3)

To all whom it may concern:

Be it known that I, Murray Block, a citizen of the United States of America, residing in New York city, county of New York, and State of New York, have invented a new, original, and ornamental Design for a Combined Wallet and Key Holder, of which the following is a specification, reference being had to the accompanying drawing, forming part thereof, wherein:

Figure 1 is a front elevational view of a combined wallet and key holder showing my new design.

Figure 2 is a side elevational view thereof showing the key holder flap in a raised position.

The rear of the combined wallet and key holder is substantially plain in appearance.

I claim:

The ornamental design for a combined wallet and key holder, substantially as shown and described.

MURRAY BLOCK.
